UNITED STATES PATENT OFFICE.

CARSTEN H. KATTENBERG, OF SAN FRANCISCO, CALIFORNIA.

CIGAR AND CIGARETTE ASH RETAINER.

1,422,578.

Specification of Letters Patent. Patented July 11, 1922.

Application filed July 6, 1920. Serial No. 394,130.

To all whom it may concern:

Be it known that I, CARSTEN H. KATTENBERG, a citizen of the United States, and a resident of San Francisco, in the county of San Francisco and State of California, have invented certain new and useful Improvements in Cigar and Cigarette Ash Retainers, of which the following is a specification.

My invention relates to a smoking tube 10 and has reference more particularly to a so-called cigar and cigarette ash retainer.

The primary object of the invention is to provide a simple and practical device in which cigars, cigarettes and even loose tobacco may be confined for smoking purposes and particularly one which will retain the burnt ashes and thus overcome the inconvenience caused when the ashes are permitted to be scattered around the room or blown 20 in the face of a person while riding in a motor or the like vehicle.

A further object of the invention is to so construct the invention that the device may be inexpensively manufactured and sold to 25 the trade as a novel and desirable article.

In the accompanying drawing Fig. 1 is a side elevation; Fig. 2 is a longitudinal section; Fig. 3 is an end view; and Figs. 4, 5, and 6 are cross sections on the lines 4-4, 30 5-5 and 6-6 respectively of Fig. 2.

Referring now to the drawing in detail, I propose to provide a tube within a tube with the outer tube 1 constructed in sections 2, 3 and 4, the section 2 constituting an end 35 closure having perforations 5 and threaded as at 6 to the section 3. The section 3 constituting the main part of the outer tube and threaded as at 7 to the section 4 which comprises the mouth piece. The various 40 sections of the outer tube may be produced from any suitable material and the same may be of any desired size. Arranged within the outer tube is the inner tube 1^a, which is

of a smaller diameter than the outer tube and having a series of lugs 8 and an annular ring 9 around its circumference to space the same from the outer tube with a cooling chamber 10 provided there around.

The inner tube may be withdrawn for cleaning purposes but is normally confined 50 in the outer tube by the end closure 2. The same also has a perforated closed end 11 and an open opposite end the periphery of which bears against the end closure.

The perforations in the closed end 11 establish a communication through the tube and the bore 12 of the mouth piece 4 so that a draft may be produced through the cigar, cigarette, or loose tobacco carried in the device. While some of the perforations 5 communicate with the cooling chamber 10 to produce the proper cooling effect the annular ring 9 and the shoulder 13 on the end 11 bearing against the shoulder 14 on the inside of the mouthpiece will go to make up a 65 tight joint at this point. The tube 1^a may be produced from any suitable heat resisting material.

I claim:

A device of the character described in 70 including a tube within a tube, the outer tube having a mouth piece and constructed in threaded sections, one of the sections comprising a perforated end closure, the inner tube having radial lugs for spacing the same 75 from the outer tube to provide a cooling chamber around the inner tube and having an open front end and a perforated opposite end, and said inner tube being produced from a heat resisting substance and 80 capable of a sliding withdrawal movement from the outer tube.

CARSTEN H. KATTENBERG.
